UNITED STATES PATENT OFFICE.

ARCHIBALD H. GOLLINGS, OF AKRON, OHIO.

DESIGN FOR A LIGHT-REFLECTOR.

50,982.

Specification for Design.

Patented July 3, 1917.

Application filed March 15, 1917. Serial No. 155,102. Term of patent 14 years.

To all whom it may concern:

Be it known that I, ARCHIBALD H. GOLLINGS, a citizen of the United States, residing at Akron, in the county of Summit and State of Ohio, have invented a new and original Design for a Light-Reflector, of which the following is a specification, reference being had to the accompanying drawings, forming part thereof.

Figure 1 is a top plan view of the reflector showing my design;

Fig. 2 is a side elevation; and

Fig. 3 is a front elevation.

I claim:

The design for a light reflector as shown.

ARCHIE H. GOLLINGS.
